UNITED STATES PATENT OFFICE.

MOÏS H. AVRAM, OF NEW YORK, N. Y.

STATEMENT-SHEET OR BILL.

1,183,835.

Specification of Letters Patent. Patented May 16, 1916.

Application filed January 3, 1916. Serial No. 70,018.

To all whom it may concern:

Be it known that I, Moïs H. AVRAM, a citizen of the United States, residing at New York, in the borough of Manhattan and 5 State of New York, have invented certain new and useful Improvements in Statement-Sheets or Bills, of which the following is a specification.

My invention relates to statement sheets 10 or bills, and is especially adapted for use with gas meters, electric meters, or the like, to furnish to the customer at any time a statement or bill as to the amount of gas, electricity, or the like which has been furnished.

More specifically the invention embodies 15 a statement sheet or bill so formed and printed, that in conjunction with an apparatus suitable for advancing the same in unison with a meter mechanism of any character, and with means for marking the same, it may be used to record automatically a quantity measure and the cost of the same to the customer since the last previous record was taken.

In the accompanying drawing the figure 20 is a plan view of my improved statement sheet or bill as used in connection with a gas meter.

In the said drawing, the sheet or bill is 25 shown formed with two rows of round holes 1, the same providing means whereby the sheet may be advanced by means of pins in a suitable feed roller connected with the meter mechanism. The space between each 30 of these holes is the distance that the meter will move the sheet during the consumption of one hundred cubic feet of gas, and oppositely disposed holes are joined by transverse lines 2 indicated on one side by the 35 number of cubic feet of gas and on the other side by the price, the same being reckoned on a basis of ten cents per one hundred cubic feet. Centrally between said holes 40 the spaces are further divided by transverse lines 3 into ten minor spaces thereby to indicate a further subdivision of the gas into units of ten cubic feet each. To the left of the left longitudinal row of holes 1 45 is a space in which is to be indicated the account number 4 of the particular meter, and in practice this number is to be punctured into the statement or bill in a manner hereinafter to be described. The statement or 50 bill is also suitably printed to denote the company controlling the same, and is pro-

vided with a space 5 to receive the customer's name and address if desired; a space 6 to show the date upon which the bill was rendered; a space 7 to indicate the date to 60 which the bill runs; a space 8 to indicate the number of cubic feet of gas used; a space 9 to give the cost of gas used; and a space 10 to receive the receipt signature for the company when the bill is paid.

At its lower end the statement or bill is 65 shown torn transversely along a perforated line 11, and it is intended that a plurality of these statements or bills are to be made up in a strip separated by transverse lines 70 of perforations to facilitate tearing the same. In practice twelve of the statements are to be inserted into the meter, thereby 75 providing a supply for one year in monthly readings, and the meter is so constructed that when the key is inserted into the door or when the door of the same is opened, it immediately causes the statement to be punctured to indicate the amount of gas consumed since the door was last opened, 80 these punctures being shown at 12 on the drawing, and indicating 3690 cubic feet. The said means which effects this puncture also punctures the account number 4, the 85 account number of the statement or bill on the drawing being 732. It will be understood that two or more of these statements or bills may be punctured at the same time, the same being in contrasting color if desired, one of which is to be dated and left 90 with the customer as a bill, and the other or others to be returned to the proper officials of the company. By perforating said statements or bills with the account number of the meter, all danger of mistake in entering 95 the account at the office of the company is obviated.

By arranging the two rows of holes 1 in 100 such position as to divide the sheet longitudinally into three spaces, I not only provide a positive feed for the statement or bill, but also apply said feed in immediate proximity to the markings indicating the amount and price of the commodity, so that the statement or bill is held firmly 105 at this point on both sides of said markings, whereby the perforation to indicate a given amount will be accurately applied without danger of any twisting or rumpling of the paper. Furthermore, by disposing 110 the amount and value designations of the commodity centrally of the statement or

bill, and providing printing matter on each side of the same, I produce a statement or bill more nearly resembling in size the gas, electric and other bills now commonly in use. And a still further important advantage is provided in my improved statement or bill, wherein, when used as a statement or bill for gas, the designation is reduced to units of ten feet, such statements or bills heretofore indicating nothing less than subdivisions of fifty feet.

Having thus described my invention, what I claim as new and desire to secure by Letters Patent, is:—

15. 1. A meter statement or bill, comprising a strip of paper provided with a double longitudinal row of holes dividing said strip longitudinally into three sections, the outer sections having printed thereon matter of any 20 desired character, and the intermediate section being divided transversely, by lines extending between said holes, into spaces indicating units of the amount of the commodity furnished, said spaces being further subdivided to indicate subdivisional units of the amount of said commodity, and one of said sections being marked to indicate that it is for the reception of a meter number.

2. A meter statement or bill, comprising a strip of paper provided with a double longitudinal row of holes dividing said strip longitudinally into three sections, one outer section having printed thereon a bill statement including the name of the creditor, and a space suitably marked to indicate that it is 35 for the name and address of the debtor, the other outer section having printed thereon a space suitably marked to indicate that it is for the receiving signature, and spaces 40 suitably marked to indicate that they are for the amount of commodity furnished and for the price of the same, one of said outer spaces having a longitudinal sub-space adjacent one of the lines of holes marked to indicate that it is for the reception 45 of a meter number and the intermediate section being divided transversely, by lines extending between said holes, into spaces indicating units of the amount of commodity furnished, said spaces being further subdivided to indicate subdivisional 50 units of the amount of said commodity.

In testimony whereof, I hereunto set my hand this 27 day of December, 1915.

MOÏS H. AVRAM.
